PORTABLE REGISTER

John Q. Sherman, Dayton, Ohio

Application August 27, 1934, Serial No. 741,580

19 Claims. (Cl. 282—3)

This invention relates to manifolding apparatus employing continuous connected stationery, and more particularly to a manifolding register suitable for sales book use or for use by deliverymen, checkers, stock-keepers, and others who have occasion to issue record slips or memoranda while moving from place to place and retain duplicate copies thereof and hence suitable to be held in the hand while making record inscriptions thereon.

In the present invention there is contemplated a box-like container for a packet of continuous strips of connected printed forms folded into zigzag formation for issuance in superposed registering relation with portions of transfer material interleaved therebetween ready to receive written inscription. Interiorly of the container there is provided automatic arresting and releasing means for retarding the advancement of the strips or forms when a predetermined length thereof has been withdrawn and facilitating the aligning and registration of the withdrawn superposed forms in writing position. The record strips and the associated transfer material are so engaged on the swinging cover of the container that they may be conveniently arranged in adjusted relation before the container is closed and the lid or cover may thereafter be raised without disarranging such materials. The terminal portions of the strips may be withdrawn from the container without raising the top or cover thereof and be disposed over such cover in detachably engaged relation therewith with the transfer material interleaved therebetween for manifolding the original inscription upon underlying forms.

Located beneath the packet container is a compartment for detached copies which is preferably formed as a separate unit to be attached to the packet container or omitted therefrom as desired, provision being made for automatically opening the storage compartment by withdrawal of succeeding portions of the record strips.

The object of the invention is to improve the construction as well as the means and mode of operation of manifolding registers and other strip dispensing apparatus, whereby they will not only be simple in construction and capable of being economically manufactured, but will be more efficient in use, capable of convenient and rapid operation, accurate in action, and unlikely to get out of repair.

A further object of the invention is to provide a manifolding register of relatively light weight, compact form, and relatively small proportions,

which can be conveniently carried from place to place.

A further object of the invention is to provide automatic aligning and registering means for the record strips whereby accurate relation of the strips in writing position may be assured.

A further object of the invention is to provide improved means for temporarily retarding the advancement of the record forms when predetermined lengths thereof have been withdrawn from the supply packet, and to automatically release the forms preparatory to further advancement under the influence of increased pulling tension thereon.

A further object of the invention is to provide improved means for mounting the interleaved transfer material and to facilitate the re-loading of the register or dispensing device when a supply packet has become exhausted.

A further object of the invention is to provide means for engaging the record strips and transfer material with the lid or cover of the packet holder, which in turn serves as a writing tablet.

A further object of the invention is to provide a convenient unitary storage compartment for detached slips which may be connected to or omitted from the packet holder as the occasion may require.

A further object of the invention is to provide a normally closed storage compartment for detached strips with means for automatically opening such storage compartment by the withdrawal of succeeding portions of the record strips preparatory to detachment of inscribed portions thereof for storage in the compartment.

A further object of the invention is to provide a strip dispensing apparatus possessing the meritorious features of construction and the desirable characteristics hereinafter mentioned.

With the above primary and other incidental objects in view, as will more fully appear in the specification, the invention consists of the features of construction, the parts and combinations thereof, and the mode of operation, or their equivalents, as hereinafter described and set forth in the claims.

Referring to the accompanying drawing, wherein is shown the preferred but obviously not necessarily the only form of embodiment of the invention, Fig. 1 is a perspective view of the portable manifolding register forming the subject matter hereof, with the withdrawn portions of the record strips disposed thereon preparatory to receiving an inscription. Fig. 2 is a perspective view showing the packet holder with its cover

or lid, forming the writing tablet, raised to upright position thereby disclosing the disposition of the packet of record strips therein and the relative arrangement of the strips and transfer material upon the lid or cover. Fig. 3 is a longitudinal sectional view. Fig. 4 is an enlarged detail view illustrating the automatic locking and release means for the loose slip storage compartment. Fig. 5 illustrates a modification of the 10 detent plate carrier.

Like parts are indicated by similar characters of reference throughout the several views.

The present manifolding apparatus is especially adapted for dispensing successive portions of 15 superposed continuous strips 1—1 of connected printed forms which are collectively folded reversely at spaced intervals into zigzag formation, forming a supply packet 2, from which the overlying forms are progressively withdrawn. The 20 strips 1 are provided with transverse division lines which may be perforated, scored, or otherwise weakened to facilitate the detachment of successive printed forms from each other. These 25 weakened division lines are preferably coincident with the reverse folds of the strips.

Interposed between the terminal portions of the record strips 1 are relatively short lengths of transfer or carbon material 3 of greater extent, however, than the length of the successive forms 30 comprising the strips and hence sufficiently long to extend beyond the first transverse division and fold lines of the strips into overlapping relation with the second set of interconnected forms. At 35 their inner ends the interleaved portions 3 of transfer or carbon material are attached to transverse supporting strips 4 of cardboard, fiber, or other suitable material, the ends of which project beyond the lateral margins of the record strips 1 for engagement with suitable anchor 40 devices within the dispensing device or register. By this means the transfer material is adapted to be fixedly secured within the register or strip dispensing device from which the transfer material portions extend in interleaved relation with 45 the terminal portions of the record strips to the exterior of the register or dispensing device and thence in reverse direction over the top thereof into writing position as will be later described.

The preferred embodiment of the autographic 50 register or strip dispensing apparatus, forming the subject matter hereof as illustrated in the drawing, comprises a box-like container 5, preferably of sheet aluminum or other light metal but which may, if desired, be constructed of fiber 55 board or other suitable sheet material. This receptacle or container 5 is of substantially equal width but of slightly greater length than the dimensions of the supply packet 2 of record material to be contained therein. One end of the 60 packet holder or container is provided with a fixed overhanging partial cover portion 6 forming in such end of the holder or container a pocket within which the packet 2 of record material is received. The packet 2 is retained in 65 such partially closed end of the holder or container by a transverse cleat 7 secured to the bottom of the container 5 in a position to project beyond the opposite end of the supply packet. The remaining open top of the holder or container 5 is provided with a swinging lid or cover 8 having dependent side flanges 9 and pivotally 70 connected at 10 to the box-like container 5. The free edge of the overhanging fixed cover portion 6 is depressed somewhat below the level of the 75 margin of the swinging cover or lid 8 when the

latter is closed whereby the margin of the lid 8 overhangs that of the fixed cover portion 6 in slightly spaced relation to afford an exit slot from the interior of the container or holder 5 through which the superposed record strips 1 may 5 be withdrawn. The swinging lid or cover 8, which is of less length than the holder or container 5, is substantially equal in length to that of the detachable forms comprising the record strips 1 and affords a writing tablet, over which 10 the withdrawn portions of the strips and the interleaved transfer material are reversely folded into writing position to receive the manifolded inscription.

Projecting from the under side of the swinging 15 cover 8 is a pair of oppositely disposed dependent stirrups 11 which project interiorly of the container 5 at opposite sides of the supply packet 2 when the lid is closed. These stirrups 11 receive the projecting ends of the mounting 20 strips 4 to which the transfer material 3 is attached to hold the transfer material stationary while the record strips are being advanced relative thereto. These mounting strips 4 are sufficiently flexible that they can be easily sprung 25 into engaging relation with the stirrups 11.

As is shown in Fig. 2, the record strips 1—1 extend from the supply packet 2 along the inner side of the cover or lid 8 and parallel therewith and between the projecting stirrups 11 beyond 30 which they continue in alternating relation with the interleaved transfer material portions 3 and the mounting strips 4. The ends of the anchor or mounting strips 4 are loosely held in the stirrups 11 which, however, retard the advancement of the transfer material in unison with the record strips. The record strips 1 and interleaved transfer material sheets 3 are collectively folded reversely about the edge of the cover or lid portion 8 coincident with the registering 40 transverse weakening division and fold lines of the respective strips, with the full length of the terminal set of registering forms disposed on the outer side of the lid or cover 8 in writing position. Each succeeding form of the respective 45 strips 1 is provided at its advanced end with spaced holes which are adapted to engage studs 12 projecting from the top of the cover 8. These engaging studs 12 have slightly reduced necks 50 whereby the heads of the studs will to a slight degree overhang the margins of the holes in the forms to resist disengagement therefrom.

In order to align the forms and yieldingly arrest the withdrawn portions in registering relation, there is provided within the receptacle or 55 container 5 a swinging member 14 which, for simplicity and convenience of manufacture, comprises a plate medially bent upon itself to parallel spaced form and pivoted as at 14' to the side walls in overlying relation with the supply packet 2. 60 This swinging aligning member is provided with a slide plate 15 mounted thereon and projected beyond the free margin of the swinging carrier by retractile springs 16 intermediate the spaced 65 reversely folded portions of the carrier plate. 70 These retractile springs are engaged with studs 17 carried by the slide plate 15 and projecting through slots 18 in the swinging carrier. Journalled in the swinging carrier immediately below the slide plate 15 is an idler roller 19 which coacts 75 with a companion idler roller 20 journalled in the container 5 to guide the record strips 1 from the supply packet 2 about the free end of the swinging carrier 14 and the sliding detent plate carried thereby into a path parallel with the under side 75

of the lid or cover 8. The swinging carrier 14 is provided with laterally extending projections or flanges 21 engaging rests upon the inner sides of the side walls of the container or receptacle 5 to support the swinging carrier in a horizontal position parallel with the top margins of the container or receptacle and with the lid or cover 8 when the latter is closed. When the cover 8 is in closed position, the margin of the sliding 5 detent plate 15 is spaced from the free edge of the lid or cover 8 a distance substantially equal to the length of one of the detachable forms. Thus as the record strips are withdrawn from the supply 10 packet 2 around the end of the swinging carrier 14, the margin of the sliding detent plate will engage in succeeding folds of the strips to yieldingly arrest the movement of the strips and press the overlying folds of the several strips into conformity with each other, while at the same time 15 the preceding set of folds conform to and enclose the free edge of the cover or lid which thereby insures accurate registry and alignment of the withdrawn portions of the strips disposed upon the lid or writing tablet in inscription receiving 20 position.

When the withdrawn portions of the strips have been inscribed and it is desired to advance the strips to present succeeding forms in writing position, the inscribed forms are disengaged from 25 the studs 12 and are preferably, though not necessarily, reversely turned off of the lid or writing tablet into extended alignment therewith and upon pulling tension being applied to the ends of the record strips beyond the terminals of the 30 transfer sheets which terminate in spaced relation with the extremities of the record strips, the latter are withdrawn from the box or container 5 relative to and independently of the transfer material. In such movement the tension upon the 35 strips will cause the detent plate 15 to be retracted, by its engagement with the enclosing folds of the strips, against the tension of the springs 16 until the margin of the detent plate is coincident with or slightly beyond the strip engaging surface 40 of the roll 19 which thereby causes the fold in the strips to be disengaged from the edge of the detent plate, permitting the strips to pass freely thereabout. As the detent plate 15 is released from the retractive pull upon the strips due to 45 disengagement of the fold therefrom, the springs 16 will again return the sliding plate 15 to its advanced position beyond the roll 19 where it is effective for restraining engagement with the next succeeding folds of the strips. By its engagement in the folds of the strips, the plate imposes sufficient resistance upon the strips to indicate to the operator that the required length of the superposed strips has been withdrawn. Furthermore, by its spring tensioned engagement in 50 the folds it imposes a slight rearward pulling tension upon the strips which tends to set the preceding fold of the strips more firmly into enclosing engagement with the free edge of the cover or writing tablet 8 to insure accurate registration 55 of the forms in writing position. To facilitate swinging movement of the detent plate carrier to enable the packet 2 to be conveniently inserted therebeneath within the container 5, the carrier is provided with a finger hole 22 into which the operator may insert his finger to lift the carrier about its pivotal connection with the container.

In order to provide space for the pivotal mounting of the swinging carrier wholly within the container 5, and to provide clearance for the 60 stirrups 11, spacers 23 are preferably, though not

necessarily, secured to the interior side walls of the container 5 and serve to hold the packet in slightly spaced relation with the side walls. Upon retractive movement of the detent plate 15 against the tension of the spring 16 under influence of pulling tension upon the strips, the roller 19 acts as a stripper to dislodge the fold from the margin of the detent plate when the latter has been retracted substantially flush with or slightly beyond the face of the roller.

In lieu of the swinging carrier 14 being of extended size and pivoted medially of the length of the container or box 5 as is illustrated in Figs. 2 and 3, this carrier or support for the detent plate 15 may be relatively short as is shown in Fig. 5, 15 and may be bodily removable from the register by having its pivotal trunnions 23^a detachably engageable in undercut slots 24 in the side walls of the box or container 5, or in the spacers 23 interiorly of such side walls. The construction 20 is the same as before described, that is to say, the plate 15 is mounted for to and fro movement upon the carrier 14^a and carries studs 17 projecting through slots 18 in the carrier, interiorly of which they are engaged with the retracting 25 springs 16. The shortened swinging carrier 14^a carries a roller 19 which performs the same function and occupies the same relative position as that previously described.

Located beneath the dispensing apparatus or 30 register is a storage compartment in which may be temporarily stored the detached sheets or sales slips. In the present instance, this storage compartment comprises a drawer 26 slidably mounted in a unitary housing 27 engageable with the under 35 side of the packet holder or register. To this end the drawer housing 27 is provided with tongues 28 of material struck therefrom which upon being projected through registering holes in the under side of the packet holder or register 40 box 5 are clenched interiorly thereof to secure the storage unit in place. Interiorly of the storage unit housing 27 there is provided an expansion spring 29 adapted to eject the drawer 26 to a partially open position to receive the detached slips. 45 The drawer 26 is normally held retracted against the tension of the ejecting spring 29 by a locking lever 30 pivoted interiorly of the packet holder 5, one end 31 of which is adapted to project through registering holes in the bottom of the packet holder and top of the storage unit housing 27 into the path of the drawer 26. The opposite end of the 50 detent lever 30 projects into the path of the plate 15, preferably, though not necessarily, by extending through a suitable hole in such plate, whereby 55 as the plate 15 is reciprocated the detent lever 30 will be oscillated about its pivotal connection.

The arrangement of parts is such that upon retraction of the detent plate 15 under influence of the springs 16 into its extended position preparatory to engagement with a fold of the record strips, the lever 30 is oscillated to thrust the locking nose 31 thereof into the path of travel of the storage drawer 26.

When, upon completion of an inscription and 65 withdrawal of a succeeding portion of the strips to renew the supply of forms in writing position, the detent plate 15 is subjected to retractive movement by the pulling tension of the strips it carries with it the locking lever 30 thereby raising 70 the detent nose 31 out of the path of the storage drawer 26, allowing such drawer to be ejected by by the reaction of the expansion spring 29. Thus the act of withdrawing a succeeding portion of the record strips automatically opens the storage 75

compartment to receive the previously inscribed detached portion of such strips.

The fixed partial cover portion 6 which overhangs one end of the packet affords a hand or 5 arm rest which is quite convenient when one must hold the register in his hand while making entries. To facilitate loading, the supply packet is confined to the end of the container by the stop cleat 7 so that the withdrawn portions of the 10 strips disposed in writing position upon the swinging cover 8 are longitudinally offset relative to the packet. When the swinging writing tablet 8 is raised the packet and coacting parts are readily 15 accessible. Cross reference is made to copending companion applications, Serial Nos. 673,207, filed May 27, 1933; 677,629, filed June 26, 1933; 729,034, filed June 4, 1934; 741,578, filed August 27, 1934; and 741,579, filed August 27, 1934.

From the above description it will be apparent 20 that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute, the 30 invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended 35 claims.

Having thus described my invention, I claim:

40 1. In a manifolding register for a packet of superposed record strips reversely folded at spaced intervals into zigzag formation and divisible on transverse weakening lines at spaced intervals into succeeding sections, a container for the pack- 45 et, said container having a packet compartment therein and being of greater length than the packet compartment, a fixed partial cover for the container, the packet receiving compartment being located in a portion of the container where 50 it is overhung by said fixed partial cover, a swinging cover portion for the container forming a writing tablet for withdrawn portions of the strips, there being an exit slot intermediate the swinging and fixed cover portions, and the writ- 55 ing tablet being longitudinally offset relative to the packet compartment, and means for anchoring transfer sheets interiorly of the container for extension through said slot and thence over the writing tablet in interleaved relation with the 60 withdrawn portion of the strips.

2. In a manifolding register for a packet of superposed record strips reversely folded at spaced intervals into zigzag formation and divisible on transverse weakening lines at spaced intervals into succeeding sections, a container for 65 said packet, said container having a packet compartment therein and being of greater length than the packet compartment, a fixed partial cover for the container, the packet receiving compartment being located in a portion to one end of the container where it is overhung by said fixed partial cover, a swinging cover portion for the container forming a writing tablet for withdrawn portions of the strips, there being an exit slot intermediate 70 the swinging and fixed cover portions, the writing

tablet being longitudinally offset relative to the packet receiving compartment, and means carried by the swinging cover portion for anchoring sheets of transfer material in interleaved relation with the withdrawn portions of the record strips. 5

3. In a manifolding register for a packet of superposed record strips reversely folded at spaced intervals into zigzag formation and divisible on transverse weakening lines at spaced intervals into succeeding sections, a container for said 10 packet, said container having a receiving compartment therein being of greater length than the packet receiving compartment, a fixed partial cover for the container, the packet receiving compartment being located in a portion of the container where it is overhung by said fixed partial cover, a swinging cover portion for the container forming a writing tablet for withdrawn portions of the strips, there being an exit slot intermediate the swinging and fixed cover portions, and the 20 writing tablet being longitudinally offset relative to the packet receiving compartment, yielding fold engaging detent means within the container engageable with succeeding folds of the strips to temporarily retard the advancement thereof when 25 a predetermined length thereof has been withdrawn, and anchor means for the transfer material carried by the writing tablet interiorly of the container.

4. A manifolding register including a container 30 for a supply packet of reversely folded superposed record strips having an exit opening through which succeeding portions of the strips may be withdrawn, a cover therefor forming a writing tablet over one end of which the withdrawn portions of the strips may be advanced into writing position, a yielding detent member disposed adjacent the opposite end of the cover and engageable with the strips to temporarily retard their movement when a predetermined 40 length thereof has been withdrawn, and a bodily removable mounting for the detent member.

5. A manifolding register including a container for a supply packet of reversely folded superposed record strips having an exit opening through 45 which succeeding portions of the strips may be withdrawn, a reciprocatory detent plate engageable in succeeding folds of the strips to temporarily retard their movement, a mounting therefor, a carrier therefor comprising a plate bent 50 upon itself to spaced parallelism, a retractile spring located within the bent plate and an extension upon the detent plate connected with the spring.

6. A manifolding register including a container 55 for a supply packet of reversely folded superposed record strips, having an exit opening through which succeeding portions of the strips may be withdrawn, a cover therefor forming a writing tablet over which withdrawn portions of the strips may be disposed in writing position, a reciprocatory 60 detent plate engageable in succeeding folds of the strips to temporarily retard their movement, a swinging carrier therefor, and means for detachably pivotally connecting the carrier with 65 the container.

7. A manifolding register including a container for a supply packet of reversely folded superposed record strips, having an exit opening through which succeeding portions of the strips may be 70 withdrawn, a cover therefor forming a writing tablet over which withdrawn portions of the strips may be disposed in writing position, a reciprocatory detent plate engageable in succeeding folds of the strips to temporarily retard their move- 75

- ment, and a detachable carrier therefor mounted within the container.
8. A manifolding register including a container for a supply packet of reversely folded superposed record strips, having an exit opening through which succeeding portions of the strips may be withdrawn, a pivotally mounted cover therefor forming a writing tablet over which withdrawn portions of the strips may be disposed in writing position, studs overlying the pivot and having slightly enlarged heads projecting from the writing tablet for engagement in correspondingly located holes in the record strips, and means underlying the pivot and within the container 10 for exerting a retractive influence upon the strips for holding them engaged beneath the heads of the studs.
9. In a manifolding register, the combination with a container for a packet of reversely folded superposed record strips transversely divisible at spaced intervals into succeeding sheets, having an exit opening for withdrawal of the strips, a relatively movable record material support within the container, and a writing tablet over which the withdrawn portions may be disposed in writing position, of a storage compartment to receive detached portions of the strips, a closure therefor, and means actuated by pulling tension upon the record strip for automatically opening the compartment, said means including a member projecting into the path of the relatively movable record material support and releasable by movement of said record material support.
10. A manifolding register, including a container for a supply of record strip material transversely divisible at spaced intervals into succeeding sheets, having an exit opening through which the strip material may be withdrawn, a member movable in response to the withdrawal of succeeding portions of the strip material from the container, a normally locked storage compartment for detached portions of the strip material, and means for automatically unlocking the storage compartment, said means being interconnected to said movable member whereby the movement of said member upon withdrawal of a portion of the strip material unlocks the storage compartment.
11. The combination with a dispensing device for strip material divisible at spaced intervals into succeeding sheets, of a storage compartment associated therewith for detached portions of the strip material, a movable strip engaging device operated by the withdrawal of the strip material, and a closure for the storage compartment controlled by the movement of said strip engaging device.
12. The combination with a dispensing apparatus for superposed reversely folded record strips divisible at spaced intervals into succeeding sheets, a yielding detent plate engageable in succeeding folds of the strips to temporarily retard their movement and adapted to yield under increased pulling tension upon the strips, a reciprocatory storage drawer associated with the dispensing apparatus for receiving detached portions of the strips, an ejecting spring for said drawer, a detent normally holding the drawer in retracted position against the tension of the ejecting spring, said drawer detent being operatively connected with said strip detent plate and disengaged from its drawer locking position by the yielding movement of the strip detent under influence of pulling tension on the strips.
13. In a manifolding register, the combination with a container for a packet of reversely folded superposed record strips transversely folded at spaced intervals, into succeeding sheets, and having an exit opening for withdrawal of the strips, a movable record material support within the container normally engaging the strips and actuated by movement of the strips, and a writing tablet over which withdrawn portions of the strips may be disposed in writing position, of a separate unitary storage compartment disposed in the bottom of the packet compartment and movable from closed to open position to receive detached portions of the strips, and locking mechanism for the maintaining of the storage compartment in closed position, said locking mechanism including means projecting into the path of the movable record material support and movable therewith to release the storage compartment locking means, simultaneously with movement of the strips.
14. In a manifolding register, the combination with a container for a packet of reversely folded superposed record strips transversely divisible at spaced intervals into succeeding sheets, having an exit opening for withdrawal of the strips, and a writing tablet over which the withdrawn portions may be disposed in writing position, of a storage compartment for detached portions of the strips and a lock for said storage compartment and release means actuated by withdrawal movement of the record strips for automatically opening the compartment simultaneously with the withdrawal of succeeding portions of the strips.
15. In a hand manifolding register a box-like container for a packet of reversely folded superposed strips of record material divisible at spaced intervals on transverse weakened lines, having an exit opening at one end thereof through which succeeding portions of the strips may be withdrawn, a cover for the container forming a writing tablet mounted to overlie the container and be supported thereon when in writing position including an edged portion engageable in a reverse fold of the strips to allocate the withdrawn portions of the strips in writing position upon the exterior face of the cover, anchor devices carried upon the underside of the cover and disposed within the container when the cover and withdrawn portions of the strips are in writing position, and transverse mounting strips engaged therewith from which transfer sheets interleaved with the record strips may extend through the exit opening of the container and thence about an edge of the cover into overlying relation therewith in interleaved relation with the withdrawn portions of the strip upon the outer face of the cover.
16. A hand manifolding register including a container of box-like form, a cover normally overlying and resting upon the container and forming a writing tablet including an edged portion about which and over the exterior face of the writing tablet superposed record strips may be extended from a supply within the container into writing position on the exterior face of said cover, said edged portion being engageable in a fold thereof to align the strips in writing position, dependent holding devices for transfer material sheets carried on the underside of the cover and extending within the container when the cover

- and record strips are disposed in writing position, from which transfer material sheets interleaved between the strips extend therewith about an edge and reversely over the exterior face of the cover.
17. A portable manifolding register including a box-like container for a supply of superposed record strips, having an outlet opening through which the strips may be withdrawn, a cover hinged thereto for swinging movement and when positioned in overlying relation with the container forming a writing tablet including an edged portion engageable in a fold of the strips when the withdrawn portions of the strips are reversely folded into writing position upon the exterior face thereof, to align the strips thereon and means supported on the interior side of the cover and within the container when the register is in condition to receive record inscriptions, for confining certain of the strips for swinging movement in unison with the cover.
18. A hand manifolding register including a box-like container for a supply of superposed record strips, having an exit opening through which succeeding portions of the strips may be withdrawn, a swinging cover forming a writing tablet overlying the container and supported thereon when it is in condition to receive record inscriptions upon withdrawn portions of the strips disposed in writing position upon the exterior face
- of the cover including an edged portion engageable in a reverse fold of the strips to locate the withdrawn portions of the strips in writing position and a series of transverse strips supported within the container and beneath the cover to which may be attached sheets of transfer material for extending intermediate the strips from the container through the exit opening and about an edge of the cover from the under to the top side thereof.
19. A hand manifolding register including a box-like container for supply of superposed record strips having an exit opening through which succeeding portions of the strips may be withdrawn, a swinging cover forming a writing tablet overlying and supported upon the container when the register is in condition to receive record inscriptions upon withdrawn portions of the strips disposed in writing position upon the exterior face of the cover including an edged portion engageable in a reverse fold of the strips to locate the withdrawn portions thereof in writing position and a series of transverse guide strips supported on the underside of the cover within the container between which said strips pass to the exit opening and thence about an edge of the cover into writing position on the exterior face thereof and confining said strips for unison swinging movement with said cover.

JOHN Q. SHERMAN. 30
